Inventor:
Mr. Vann Garrison.

UNITED STATES PATENT OFFICE.

VERNA GARRISON, OF NORTON, KANSAS.

DOOR-OPENING MECHANISM.

Application filed February 20, 1924. Serial No. 694,180.

This invention relates to vehicle operating mechanism for opening doors, gates and the like.

The object of the invention is to provide a simple and efficient door opening mechanism operable from either side of the closure by the weight of the vehicle as it approaches the closure, the door closing automatically after the vehicle passes a predetermined point.

This invention is primarily intended for use in connection with garage doors but may be used equally well on gates.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

25 In the accompanying drawings:—

Figure 1 represents a front elevation of a garage equipped with this improved mechanism the door being shown in closed position.

30 Fig. 2 is a horizontal section taken on the line 2—2 of Fig. 1.

Fig. 3 is a vertical section taken on the line 3—3 of Fig. 2.

Fig. 4 is a transverse section through a building equipped with the invention applied to sliding or rolling doors, the doors shown in closed position; and

Fig. 5 is a view similar to Fig. 3 showing the rolling doors.

40 In the embodiment illustrated in Figs. 1 to 3 outwardly swinging hinged doors 1 and 2 are shown for closing a garage 3 and which are equipped with coiled springs 4 and 5 connecting the inner faces of the upper ends of the doors with the door jambs as shown at 6. These springs exert their tension to close the doors as shown in the drawings.

The opening mechanism comprises two longitudinally extending boards 7 and 8 arranged to extend through the opening in which the doors 1 and 2 are located and which project some distance into the garage and some distance outside thereof so that

55 vehicles approaching the garage will pass

over one end of the boards and over the other ends after entering the garage.

These boards are spaced laterally apart a distance corresponding to the distance between the wheels on opposite sides of the vehicle so as to insure the vehicle wheels passing over the boards.

A crank shaft 10 is arranged transversely of the track formed by the boards 7 and 8 inside the garage at a point spaced from the opening designed to be closed by the doors 1 and 2. This shaft is mounted for rocking movement in suitable bearings the crank portions 11 and 12 of the shaft being located under plates 9 carried by the inner ends of boards 7 and 8 said plates having a loose connection with the cranks 11 and 12 so that when the shaft 10 is turned in one direction the inner ends of the boards will be raised and when turned in the other direction these ends will be lowered. The free ends of these plates 9 are preferably inclined downwardly to facilitate the passage of the vehicle wheels onto the boards when coming out of the garage.

The shaft 10 is provided at its opposite ends with upstanding right angular arms 13 here shown equipped at their free ends with eyes 14 with which are engaged similar eyes carried by rods 15. These rods 15 are shown extended through openings 3^a in the front wall of the garage adjacent the hinged upper ends of the doors. Rods 16 are located transversely across the upper ends of the doors 1 and 2 being connected with the doors near their free edges as shown at 17. The rear ends of these rods extend across the hinged ends of the doors and have a loose connection with the links 15 so that when the crank portions 11 and 12 of the shaft 10 are moved downwardly by pressure exerted on the plates 9 or on the outer ends of the track bars 7 and 8 the shaft will be rocked and a pull transmitted through the links 15 to the rods 16 causing the doors 1 and 2 to swing outwardly against the tension of the springs 4 and 5. The doors will remain in this position as long as the crank shaft is depressed and when pressure is removed therefrom the springs 4 and 5 will operate to close the doors 1 and 2 and to return the crank shaft to its normal position raising the track boards 7 and 8 ready for the next vehicle.

In the use of this mechanism the parts

being in the position shown in Figs. 1 to 3 a vehicle approaching the garage and passing up onto the boards 7 and 8 will depress the boards sufficiently to rock shaft 10 and 5 lower the crank portions 11 and 12 exerting sufficient pull on the rods 15 and 16 to open the doors 1 and 2 against the tension of the springs 4 and 5.

After the vehicle enters the garage over 10 tracks 7 and 8 and passes off the inner ends of said tracks the doors 1 and 2 will automatically close under springs 4 and 5.

When the vehicle is to be taken out of the garage the driver will steer it on to the 15 plates 9 and the weight of the vehicle will depress the bars 7 and 8 and rock the crank shaft 10 a sufficient distance to open the doors 1 and 2 permitting the vehicle to pass 20 out of the garage the doors being held open until the vehicle passes off bars 7 and 8.

It is of course understood that the doors 1 and 2 may be opened by hand and held in open position by props or any suitable means.

25 In the form shown in Figs. 4 and 5 the doors 1^a and 2^a are mounted on rollers 18 to travel on a track 19 located inside the building which is equipped with the doors 1^a and 2^a. These doors are held normally 30 closed by a coiled spring 20 secured at its opposite ends to the respective doors spanning the front edges thereof as shown in Fig. 4.

The operating mechanism for these doors 35 is the same as that shown in the other figures except that the links 15 and rods 16 are dispensed with and cables 21 used to replace them. These cables 21 are connected with the upper ends of the shaft arms 13 and 40 pass over pulleys 22 located on the inner wall of the building and are attached to the

upper front corners of the doors 1^a and 2^a so that when the crank shaft 10 is rocked a pull will be transmitted through arms 13 and the cables 21 to the doors 1^a and 2^a, said 45 pull being sufficient to overcome the tension of spring 20.

The same crank shaft 10 is used in connection with either the hinged or the sliding doors. 50

This door opening mechanism obviously may be used for opening farm gates equally as well as the doors of buildings and avoids the necessity of the driver getting out to open gates, garage doors and the like. 55

I claim:—

A closure operator for buildings including boards defining a track and having their inner ends supported within the building, the ground surface under the boards being 60 cut away throughout substantially the entire lengths of the boards, a crank shaft supported within the building, said boards having their inner ends resting on the cranks of the crank shaft, said crank shaft having upwardly extended end portions disposed at right angles to the cranks, rods connected with the upwardly extended end portions, said rods being inclined and having their outer ends arranged adjacent to the upper 65 ends of closures for the building, rods connected with the first mentioned rods, and extending across the upper portions of the closures and connected with the closures at points adjacent to the free edges of the 70 closures, and said rods adapted to exert a pull on the closures when the boards are depressed under the weight of a vehicle. 75

In testimony that I claim the foregoing as my own, I have hereto affixed my signature.

VERNA GARRISON.
